CLAIM

The ornamental design for a game tower, as shown and described.

DESCRIPTION

FIG. 1 is a front perspective view from above of the claimed design in an environment;

FIG. 2 is a front view of the claimed design of FIG. 1;

FIG. 3 is a rear view of the claimed design of FIG. 1;

FIG. 4 is a right side view of the claimed design of FIG. 1;

FIG. 5 is a left side view of the claimed design of FIG. 1;

FIG. 6 is a top plan view of the claimed design of FIG. 1; and,

FIG. 7 is a bottom plan view of the claimed design of FIG. 1.

The broken line showing of portions of the game tower depicts environment and forms no part of the claim.
